MARBLE SHOOTING COASTER TOY
WITH PROJECTOR

Frederick J. Scharkopf, Valley Stream, N. Y.

Application December 17, 1947, Serial No. 792,216

7 Claims. (Cl. 46—43)

1

This invention relates to improvements in toys, and particularly toys which employ marbles for different tests of skill.

One of the objects of the invention is the provision of an apparatus or device having an upper and a lower runway, and a projector for imparting a vertical lifting motion to a marble, so that the player can by skillful operation cause a marble to enter the upper runway, and then descend by gravity and by the impulse imparted by projection, to the lower runway.

Another object of the invention is the provision of a toy apparatus or device with an upper and a lower runway, a spring for projecting a marble or small sphere from the lower runway to the upper runway, and a deflector disposed directly above the spring for causing the projected marble or sphere to enter the upper runway and roll downwardly and then enter the lower runway.

A further object of the invention is the provision of a toy apparatus or device, having an upper and a lower runway, means for projecting a marble or sphere to the upper runway, and a direction controlling switch for causing the marble to roll out of the device from the upper runway or roll into the lower runway.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevation of the improved projecting marble toy, showing in dot and dash, the course of action the marble will take if properly directed by pressure on the finger hold.

Fig. 2 is a top plan view thereof.

Fig. 3 is a vertical longitudinal sectional view.

Fig. 4 is a horizontal sectional view, taken on line 4—4 of Fig. 1, looking in the direction of the arrows.

The toy, according to the present invention, includes a channel shaped base 10 having vertical flanges 11 and 12 and a table 13.

On the table 13 a lower runway 14 is supported in slightly inclined relation thereto, so that its lower end 14^a will be held close to the table 13, and its upper end 14^b will be spaced above the same.

A U-shaped stop 15 is mounted on the table so as to straddle the lower end 14^a of the runway 14.

2

and projects above the same a considerable distance to act as a deflecting wall. The higher end 14^b of the runway 14 is supported between vertical side walls 16 and 17 of a housing 18. The side walls 16 and 17 are secured by bottom flanges 19 to the table 13. The upper ends of the sides 16 and 17 are connected to each other by an inclined top wall 20.

Near the stop 15 two standards 21 and 22 are secured by means of base angles 23. Between the upper ends of these standards 21 and 22 an inverted U-shaped deflector hood 24 is supported, and adjacent the lower edge of this deflector 24 the upper end of an upper runway 25 is supported, as by the rivets 26.

The deflector hood 24 is provided with side walls 27, a concave curved top wall portion 29, and a downwardly inclined top wall portion 30, which is supported directly over the vertical U-shaped stop 15. The concave top wall portion 29 is supported directly over the upper end of the upper runway 25.

The downwardly inclined portion 30 forms a guiding surface to give lateral shifting movement 25 to a marble thrown or projected against the same, and the concave roof surface imparts a downward shift to the marble, to cause it to drop onto the upper runway 25.

The lower end of the upper runway 25 is supported between the vertical side walls 16 and 17 of the housing 18. Between the side walls 16 and 17 a switch plate 32 is pivotally supported on the shaft or rod 33, so that the inner end 32^a of said plate may be swung under and against the lower end of the upper runway 25, or against the uppermost end 14^b of the lower runway 14. A lever 34 is fixed to the outer end of the shaft or rod 33, and is adapted to swing against a spring latch or retainer 35, which is secured to the housing 40 18, by a rivet 36.

A vertical hole 37 is formed in the lower end 14^a of the lower runway 14, and a flat metal spring 38 is secured to the underside of the table 13, and extends outwardly thereof to provide a finger hold 39, by means of which the spring 45 may be depressed. This spring normally lies against the bottom side of the table 13, and thus extends across the hole 37. By placing a marble in the hole 37 and depressing the spring 38 by the finger hold 39 and then quickly releasing the finger hold, the marble will be projected upwardly through the hole 37, and will rise above the lower runway 25.

If the player makes a very quick release of the spring 55 after it has been placed under maximum

tension, by bending downwardly, the marble will be projected against the inclined top wall portion 30, will roll upwardly toward the concave top wall portion 29, and be deflected into the upper runway 25, rolling down this runway.

By placing the inner end 32^a of the switch plate 32 in engagement with the upper end 14^b of the lower runway 14, the marble will be caused to roll into the lower runway and return to the lower end of the same, where it will again enter the projection hole 37, and may again be projected. This course of action is seen in dot and dash lines in Fig. 1 showing the course of travel the marble would take if the finger hold 39 were depressed.

By swinging the switch plate 32 so that the inner end 32^a of the same will engage the lower end of the upper runway 25, the marble will be deflected outwardly of the device, into any external ball game field organized upon a floor, sidewalk or field, and the velocity of rolling given to the ball by the force of the reaction of the flat spring 38 will govern the distance of travel from the device, over any external game field; the position of the switch plate 32 being governed by the lever 34.

When the lever 34 is engaged with the latch 35, the switch plate 32 will occupy a position to deflect the rolling marble from the upper runway 25 to the lower runway 14.

The toy device provides means for making competitive tests of skill, and to enable children to exercise their natural desire to apply force to objects, without exposing themselves or others to injury.

Each of the runways is of U-shaped construction, so that one or a number of marbles may be used in operating the device, and so that no marble will be displaced from the device.

While I have illustrated and described the preferred embodiments of my invention, it is to be understood that I do not limit myself to the precise constructions herein disclosed and the right is reserved to all changes and modifications coming within the scope of the invention, as defined in the appended claims.

Having thus described my invention, what I claim as new, and desire to secure by United States Letters Patent is:

1. A marble projecting toy, comprising a base of channel construction, a U-shaped housing supported on the base near one end thereof, a pair of standards supported on the base near the opposite end thereof, a U-shaped inclined runway having an upper end supported on the standards and a lower end supported in the housing, a second U-shaped inclined runway beneath said first runway and having an upper end supported in the housing spaced beneath the lower end of said first runway and a lower end disposed against the base adjacent the standards, said base and said second named runway having a hole located near the lower end thereof, a deflector supported on the standards above the upper end of the first runway and provided with an upwardly inclined lower end located directly over the hole and a downwardly curved upper end located directly over the upper end of the first named runway, manually operable means on said base for projecting a marble upward through the hole against the deflector to be deflected by said deflector onto said upper runway to roll down the same, a switch plate pivoted on a horizontal axis intermediate of its ends in the housing between the adjacent ends of said runways to be turned to a position engaging the

lower end of said upper runway to deflect a ball rolling down the upper runway off the lower end thereof or to be turned to a position engaging the upper end of said lower runway to deflect a ball rolling down said upper runway onto said lower runway, a lever connected with the switch plate for swinging the same from one position to the other, and a spring latch disposed against the housing for securing the lever in one position.

2. A toy comprising a table, a pair of spaced standards mounted on one end of said table, an inverted U-shaped housing mounted on the other end of said table, an inclined upper runway supported between said standards and said housing with its high end between said standards and with its low end projected into the adjacent end of said housing, an inclined lower runway supported between said standards and said housing with its high end in said housing and spaced beneath the low end of said upper runway and with its low end between said standards, means at the high end of said upper runway for deflecting a vertically projected ball onto the high end of said upper runway to roll freely down the same, means at the low end of said lower runway for projecting a ball vertically toward said deflecting means, and manually controllable means in said housing between the adjacent ends of said runways for directing a ball rolling down the upper runway off the lower end thereof or onto the upper end of said lower runway to then roll down the lower runway.

3. A toy comprising a table, a pair of spaced standards mounted on one end of said table, an inverted U-shaped housing mounted on the other end of said table, an inclined upper runway supported between said standards and said housing with its high end between said standards and with its low end projected into the adjacent end of said housing, an inclined lower runway supported between said standards and said housing with its high end in said housing and spaced beneath the low end of said upper runway and with its low end between said standards, means at the high end of said upper runway for deflecting a vertically projected ball onto the high end of said upper runway to roll freely down the same, means at the low end of said lower runway for projecting a ball vertically toward said deflecting means, and manually controllable means in said housing between the adjacent ends of said runways for directing a ball rolling down the upper runway off the lower end thereof or onto the upper end of said lower runway to then roll down the lower runway, said manually controllable means, comprising a shaft rotatively supported between the side walls of said housing parallel to and between the adjacent ends of said runways, a switch plate fixedly mounted on said shaft between the side walls of said housing to turn with said shaft to a position in which the end of the switch plate adjacent said runways engages the upper runway to direct a ball off the end of the upper runway or to a position in which the end of the switch plate adjacent said runways engages the lower runway to direct a ball onto said lower runway.

4. A toy comprising a table, a pair of spaced standards mounted on one end of said table, an inverted U-shaped housing mounted on the other end of said table, an inclined upper runway supported between said standards and said housing with its high end between said standards and with its low end projected into the adjacent end of said housing, an inclined lower runway supported

between said standards and said housing with its high end in said housing and spaced beneath the low end of said upper runway and with its low end between said standards, means at the high end of said upper runway for deflecting a vertically projected ball onto the high end of said upper runway to roll freely down the same, means at the low end of said lower runway for projecting a ball vertically toward said deflecting means, and manually controllable means in said housing between the adjacent ends of said runways for directing a ball rolling down the upper runway off the lower end thereof or onto the upper end of said lower runway to then roll down the lower runway, said manually controllable means, comprising a shaft rotatively supported between the side walls of said housing parallel to and between the adjacent ends of said runways, a switch plate fixedly mounted on said shaft between the side walls of said housing to turn with said shaft to a position in which the end of the switch plate adjacent said runways engages the upper runway to direct a ball off the end of the upper runway or to a position in which the end of the switch plate adjacent said runways engages the lower runway to direct a ball onto said lower runway, said shaft having an end extended from one side of said housing, and a handle fixed to the extended end of said shaft for turning said shaft between either of the two positions of said switch plate.

5. A toy comprising a table, a pair of spaced standards mounted on one end of said table, an inverted U-shaped housing mounted on the other end of said table, an inclined upper runway supported between said standards and said housing with its high end between said standards and with its low end projected into the adjacent end of said housing, an inclined lower runway supported between said standards and said housing with its high end in said housing and spaced beneath the low end of said upper runway and with its low end between said standards, means at the high end of said upper runway for deflecting a vertically projected ball onto the high end of said upper runway to roll freely down the same, means at the low end of said lower runway for projecting a ball vertically toward said deflecting means, and manually controllable means in said housing between the adjacent ends of said runways for directing a ball rolling down the upper runway off the lower end thereof or onto the upper end of said lower runway to then roll down the lower runway, said manually controllable means, comprising a shaft rotatively supported between the side walls of said housing parallel to and between the adjacent ends of said runways, a switch plate fixedly mounted on said shaft between the side walls of said housing to turn with said shaft to a position in which the end of the switch plate adjacent said runways engages the upper runway to direct a ball off the end of the upper runway or to a position in which the end of the switch plate adjacent said runways engages the lower runway to direct a ball onto said lower runway, said shaft having an end extended from one side of said housing, and a handle fixed to the extended end of said shaft for turning said shaft between either of the two positions of said switch plate, and means for holding said handle in a position in which said switch plate engages said lower runway.

6. A toy comprising a table, a pair of spaced standards mounted on one end of said table, an inverted U-shaped housing mounted on the other

end of said table, an inclined upper runway supported between said standards and said housing with its high end between said standards and with its low end projected into the adjacent end of said housing, an inclined lower runway supported between said standards and said housing with its high end in said housing and spaced beneath the low end of said upper runway and with its low end between said standards, means at the high end of said upper runway for deflecting a vertically projected ball onto the high end of said upper runway to roll freely down the same, means at the low end of said lower runway for projecting a ball vertically toward said deflecting means, and manually controllable means in said housing between the adjacent ends of said runways for directing a ball rolling down the upper runway off the lower end thereof or onto the upper end of said lower runway to then roll down the lower runway, said manually controllable means, comprising a shaft rotatively supported between the side walls of said housing parallel to and between the adjacent ends of said runways, a switch plate fixedly mounted on said shaft between the side walls of said housing to turn with said shaft to a position in which the end of the switch plate adjacent said runways engages the upper runway to direct a ball off the end of the upper runway or to a position in which the end of the switch plate adjacent said runways engages the lower runway to direct a ball onto said lower runway, said shaft having an end extended from one side of said housing, and a handle fixed to the extended end of said shaft for turning said shaft between either of the two positions of said switch plate, and a latch mounted on the side wall of said housing from which the end of said shaft extends to be engaged by said handle for holding said switch plate in a pivoted position engaging said lower runway.

7. A toy comprising a table, a pair of spaced standards mounted on one end of said table, an inverted U-shaped housing mounted on the other end of said table, an inclined upper runway supported between said standards and said housing with its high end between said standards and with its low end projected into the adjacent end of said housing, an inclined lower runway supported between said standards and said housing with its high end in said housing and spaced beneath the low end of said upper runway and with its low end between said standards, means at the high end of said upper runway for deflecting a vertically projected ball onto the high end of said upper runway to roll freely down the same, means at the low end of said lower runway for projecting a ball vertically toward said deflecting means, and manually controllable means in said housing between the adjacent ends of said runways for directing a ball rolling down the upper runway off the lower end thereof or onto the upper end of said lower runway to then roll down the lower runway, said manually controllable means, comprising a shaft rotatively supported between the side walls of said housing parallel to and between the adjacent ends of said runways, a switch plate fixedly mounted on said shaft between the side walls of said housing to turn with said shaft to a position in which the end of the switch plate adjacent said runways engages the upper runway to direct a ball off the end of the upper runway or to a position in which the end of the switch plate adjacent said runways engages the lower runway to direct a ball onto said lower runway, said housing having a top wall inclined par-

allel to said top runway and said switch plate being of a length so that when its end between said runways engages said lower runway its other end will engage the lower end of said top wall closing the end of said housing remote from said runways.

FREDERICK J. SCHARKOPF.
